UNITED STATES PATENT OFFICE.

JOHN B. HADAWAY, OF BROCKTON, MASSACHUSETTS, ASSIGNOR TO THE GEM FLEXIBLE INSOLE COMPANY, OF BOSTON, MASSACHUSETTS.

INSOLE-REINFORCING MACHINE.

SPECIFICATION forming part of Letters Patent No. 614,860, dated November 29, 1898.

Application filed November 3, 1897. Serial No. 657,236. (No model.)

To all whom it may concern:

Be it known that I, JOHN B. HADAWAY, a citizen of the United States, residing at Brockton, in the county of Plymouth and State of Massachusetts, have invented certain new and useful Improvements in Insole-Reinforcing Machines; and I do hereby declare the following to be a full, clear, and exact description of the invention, such as will enable others skilled in the art to which it appertains to make and use the same.

The present invention relates to boot and shoe machinery, and more particularly to a machine for applying a reinforcing-covering to insoles, and relates to certain improvements in the form and arrangement of the machine disclosed in my former applications for Letters Patent of the United States, filed on the 23d day of December, 1895, Serial No. 572,972, and the 14th day of February, 1896, Serial No. 579,296.

The object of the present invention is to produce a more compact and simplified machine and to improve the operation of the several mechanisms, whereby the machine is capable of a greatly-increased product and will be easy and quick in action.

To the above end the present invention consists of the devices and combination of devices which will be hereinafter described and claimed.

The present invention is illustrated in the accompanying drawings, in which similar letters of reference designate corresponding parts, and in which—

Figure 1 shows a side elevation of the machine looking from the right of Fig. 3, portions of the pulley and hand-wheel being broken away and also the lower portion of the standard. Fig. 2 shows a view of the opposite side of the machine. Fig. 3 shows a front elevation of the machine. Fig. 4 shows a section of the forward part of the machine below the line $x-x$ in Fig. 3, showing the stretching-tool in plan, the cutting mechanism being omitted. Fig. 5 represents a vertical section through the work-support.

In the drawings, A represents a standard or base, upon the upper end of which is mounted a frame or head A', which carries the operative parts of the machine. The head A'

is provided with upwardly-extending standards a , which at their upper ends are provided with suitable bearings a' , in which is mounted the main shaft B, said shaft carrying upon its rear end a pulley b and at its forward end a combined cam and hand wheel b' and between its bearings a cam-drum b^2 . Projecting from the front of the machine is a bracket b^3 , which carries a bearing b^4 , in which is received the shank c of a work-support C, which is rotated step by step by mechanism which will be hereinafter described.

The machine of the drawings comprises a presser-tool D, which is carried by a bell-lever d , which is fulcrumed at d' upon the fixed frame of the head A' and which at its opposite end carries an antifriction-roll d^2 , which engages a cam-groove b^5 cut in the cam-drum b^2 , whereby upon a rotation of the shaft B said bell-lever d will be oscillated and impart an up-and-down movement to the presser-tool D to alternately clamp and release the work which is superimposed upon the work-support C.

In order that the presser-tool D may yield vertically as it contacts with the insole, the shank of said tool is fitted in a guideway d^3 to have a free sliding movement therein, said movement being limited by a stud d^4 , carried by said shank, which engages a slot d^5 in a retaining-plate d^6 , the upper end of the shank being acted upon by a spring d^7 , which is secured to the side of guide d^3 . For the purpose of providing for an adjustment of the presser-tool D toward and from the bead-forming tools to provide for insoles of various widths of feather the guide d^3 is provided with a shank d^8 , and one end of the lever d provided with slots d^9 to receive the set-screws d^{10} , which take into screw-threaded apertures in the shank d^8 and by means of which the guide d^3 is adjustably secured to said lever. The above-described arrangement is such that a rotation of the shaft B will by means of the bell-lever d impart a movement to the presser-tool D toward and from the insole superimposed upon the work-support C and press the reinforcing material against the inner face of the lip or against the end of the former or anvil, which will be hereinafter described.

75

80

85

90

95

100

The anvil or former E consists of a thin plate of metal which is secured to a support e by a set-screw e' and has upon its outer end a tapering upturned bead, forming projection 5 or finger e², the said finger being upwardly and outwardly bent, as clearly shown in Figs. 1 and 2, and extends over the work-support C in position to be projected beneath the reinforcing material, over which the reinforcing 10 material is formed by the presser-tool and bead-forming tools, as will be fully described.

Coöperating with the anvil or former E is a movable bead-forming tool F and a fixed tool G, the movable tool F acting to bend down 15 and press the reinforcing material over the anvil or former to form the bead or crimp therein, and the fixed tool G is secured to the front of frame A' by a set-screw g and acts upon the insole after it has been acted upon 20 by the movable tool F and, resting against the outer side of the bead or crimp, acts as a guide for the work, and the lower end gives a final smoothing and pressing to the reinforcing material upon the feather.

25 The tool F comprises a tapering plate of metal f, which at its lower end has a finger f', which is arranged to pass downwardly alongside of and close to the bead-forming finger e² of the former or anvil E to bend the reinforcing material over said bead-forming finger, and said tool also comprises a thin plate f², which is affixed in position in front of the plate f, the lower end of the thin plate f² being considerably wider than the finger f' on 30 the plate f and terminating in a bent portion f³ slightly above the end of the finger f' in position to act upon the reinforcing material upon the upper surface of the finger e² of the anvil or former E. The finger F is secured 35 to the front of a vertically-reciprocating slide f⁴ by the set-screw f⁵, which passes through slots (not shown) formed in the upper ends of the plates f and f², the upper end of the bead-forming tool F being acted upon by a screw- 40 stop f⁶, threaded in a bearing f⁷, formed upon the front of the slide f⁴, whereby said tool F is fixedly held in position and may be accurately adjusted upon the slide f⁴. The slide f⁴ is arranged for vertical reciprocation in a 45 guideway f⁸ (see dotted lines, Fig. 3) and carries at its upper end a cam-roll f⁹, which takes into a cam-path formed in the rear face of the cam-disk b⁶, forming a part of the combined cam and hand wheel b', whereby said slide f⁴ is reciprocated vertically to impart a movement 50 to the bead-forming tool F toward and from the work upon the work-support C.

In order to impart a lateral movement to the bead-forming tool F to coöperate with the 55 work-support C in feeding the work, the guideway f⁸ is formed in a horizontally-sliding block f¹⁰, held in a horizontal guideway f¹¹, formed in the front of a fixed portion of the head A' and held in said guideway by 60 suitable retaining-plates f¹² or in any other suitable manner.

The horizontal movement of the block f¹⁰ is

imparted by a two-arm lever f¹³, fulcrumed at f¹⁴ upon a stud f¹⁵, which is fixedly secured in a pinch-clamp f¹⁶, carried by an arm f¹⁷, 70 projecting from the fixed head A'. The lower end of the lever f¹³ is forked and embraces a stud f¹⁸, mounted in an ear f¹⁹, formed on the block f¹⁰, and the upper end of the lever f¹³ carries a cam-roll f²⁰, which engages a cam-path f²¹, formed in the front face of the cam-drum b². The above-described arrangement is such that a rotation of the main shaft B will, by means of the cam-path f²¹ and the lever f¹³, impart a horizontal reciprocating movement to the block f¹⁰, carrying the guideway f⁸, thereby imparting the lateral reciprocation to the bead-forming tool F, and at 75 the same time the vertical reciprocation is imparted to the tool F by the cam b⁶ acting upon the slide f⁴. The work-support C may be simply mounted to have a free rotary movement in the bearing b⁴ and be rotated by the frictional engagement of the work against the surface thereof as said work is forced thereagainst by the bead-forming tool F; but to insure perfect accuracy in the feed of the work the work-support C is arranged to be positively rotated step by step in the direction of the feed of the work and in unison with the movement of the bead-forming tool F in the same direction. The work-support C, as before explained, has a shank c, which is fitted to rotate in the bearing b⁴, and said work-support C is held elevated by a spring 100 which acts on a head which receives and supports the shank c, whereby said work-support C is forced upwardly to clamp the work against the fixed tool G.

The shank c of the work-support C is loosely 105 connected with a rod c', which is connected by a wire or chain c² to a treadle, (not shown,) whereby the work-support C may be depressed for the purpose of placing the work thereon under the bead-forming tools. Within the 110 bearing b⁴ is a sleeve c³, which is mounted to rotate therein and in which the shank c is directly received, the said shank being freely vertically movable therein, but splined to said sleeve c³ to turn therewith.

Upon the lower end of the sleeve c³, below the bearing b⁴, is mounted a ratchet-disk c⁴, rigidly secured to the sleeve c³. Above the ratchet-disk c⁴ is a loose collar c⁶, which is arranged to be freely movable about the sleeve 120 c³ and which has a projecting lug c⁷, carrying a pawl c⁸, which is held by a spring c⁹ against the ratchet-disk c⁴.

In order to oscillate the collar c⁶ to cause the pawl c⁸ to rotate the ratchet-disk c⁴, said 125 collar is connected to a link c¹⁰, which is pivotally connected at c¹¹ to the lug c⁷, and at its opposite end is pivotally connected to a stud c¹², carried by the arm c¹⁴ of a bell-crank lever c¹⁵. The bell-crank lever c¹⁵ is fulcrumed 130 at c¹⁷ upon a stud or post c¹⁸, and the other arm c¹⁹ thereof is provided with a segment-gear c²⁰, as clearly shown in Figs. 2 and 4.

The bell-crank lever c¹⁵ is actuated by a

two-armed lever c^{21} , which is fulcrumed upon a stud c^{22} , held in a pinch-clamp c^{24} upon the fixed frame or head A' .

The lower arm c^{25} of the lever c^{21} has a segmental gear c^{26} , which is in mesh with the gear c^{20} of the lever c^{15} , and the upper arm c^{27} of the lever c^{21} carries a cam-roll c^{28} , which engages a cam-path (not shown) formed in the rear face of the cam-drum b^2 .

- 10 The above-described arrangement is such that a rotation of the main shaft B will, by means of the lever c^{21} , impart an oscillation to the bell-crank lever c^{15} , which will impart a reciprocating movement to the link c^{10} , which 15 will oscillate the collar c^6 upon the sleeve c^3 and cause the pawl c^8 to rotate the ratchet-disk c^4 , and thus impart a step-by-step rotation to the work-support C , the rotation being simultaneous with the lateral movement 20 of the bead-forming tool F in the direction of the feed, whereby the insole, which is clamped between the work-support C and the bead-forming tool F , will be fed step by step to bring successive portions of the edge of the 25 sole in position to be acted upon by the bead-forming tools.

In the formation of the bead or crimp the anvil or former E is projected beneath the edge of the reinforcing material, and in order 30 to facilitate the proper positioning of the work and its removal from the machine without the liability of displacing the reinforcing material along the edge of the sole the former or anvil E is arranged to have a vertical movement toward and from the bead-forming tools with 35 the work-support, and such movement is preferably accomplished by the movement of the work-support by the following mechanism: The upward movement of the work-support C is controlled by an adjustable stop h , which is secured fixedly to the rod c' and which strikes 40 against an adjustable stop h' , shown as a nut or sleeve h^2 , secured in a bearing h^3 , carried by a bracket h^4 , projected from the front of 45 the frame A' . Connected to the rod c' below the stop h is clamp h^5 , which is provided with a projecting arm h^6 , carrying at its outer end an eye h^7 , which receives a rod h^8 and along which said eye is free to move. The 50 rod h^8 is pivotally connected at h^9 to the support e of the anvil or former E , said support e being fulcrumed at e^3 to a standard e^4 , projecting upwardly from the base of the head A' and which is secured on said base by the 55 screws e^5 , (one only being shown,) whereby the standard and support e may be adjusted back and forth to vary the position of the anvil or former E relatively to the work-support C and to bring its bead-molding finger e^6 directly 60 in line with the outer plate f^2 of the bead-forming tool F . The rod h^8 is provided with a stop-nut h^{10} , which is threaded upon the end thereof below the eye h^7 and at its upper end is surrounded with a coiled spring h^{11} , which 65 bears at one end against a nut h^{12} on said rod and at its lower end against a rest or guide h^{13} , carried by an arm h^{14} , projected from the

standard e^4 , and said rod h^8 carries a stop-nut h^{15} below the guide h^{13} , which forms a stop to limit the upward movement of the rod h^8 and 70 the anvil or former E .

The stop h^{10} is preferably arranged upon the rod h^8 at a short distance below the eye h^7 , so that the rod c' may be moved downward slightly before the eye h^7 comes in contact 75 with the nut h^{10} to cause a downward movement of the rod h^8 , and thus the work-support C may be depressed slightly without imparting any movement to the anvil or former E , such depression causing the work-support 80 to move away from the anvil or former a sufficient distance to permit the insertion of the edge of the shoe-sole between the upper surface of the work-support and the under surface of the former or anvil. The above-described arrangement is such that a downward movement of the rod c' will move downward the work-support C , moving said work-support away from the anvil or former to release the work, and when the eye h^7 comes into contact with the nut h^{10} the rod h^8 will be drawn down against the tension of the spring h^{11} and move the support e about its fulcrum e^3 , thus causing the forward end of the anvil or former E to move downward with the work-support 95 C in the further movement of said work-support. Upon the release of the work-support it will be moved upward by its spring and at the same time the spring h^{11} will raise the anvil or former, its upward movement being limited by the stop-nut h^{15} .

Cooperating with the bead-forming tool is a stretching device which is arranged to engage and stretch the projecting edge of the reinforcing material just prior to its being 105 acted upon by the bead-forming tools, so as to remove all surplus material and insure the even and smooth application of the reinforcing material to the insole. This stretching device consists of a roughened foot or tool k , 110 which is secured to the downturned end k' of a shank k^2 , said shank at its opposite end being adjustably secured by means of a slot k^3 and screw k^4 to a short lever k^5 , which is fulcrumed upon a stud k^6 , whereby the shank k^2 115 is arranged to have a vertical movement to move the stretching foot or tool k toward and from the anvil or former E . The stretching-tool k is also arranged to have a movement in an inclined or oblique direction across the 120 reinforcing material which may be superimposed upon the anvil or former and also a movement toward and from the medial line of the insole, and such movements in the machine of the drawings may be conveniently 125 produced by the following mechanism:

The vertical movement of the stretching-tool k is imparted in an upward direction by an arm or bracket k^7 , which is secured by a screw k^8 to the side of the slide f^4 of the bead-forming tool F and projects laterally therefrom across the front of the machine, then backwardly and downwardly, and thence inwardly beneath the shank k^2 of the stretching-tool 130

5 *k*. A spring k^8 is secured at one end to the lever k^5 and at its opposite end to an eye k^9 , carried by the link c^{10} , the spring k^8 acting to impart to the stretching-tool k a yielding downward movement to cause said tool k to engage the reinforcing material.

10 The movement of the tool k toward and from the medial line of the insole is imparted by the bell-crank lever c^{15} , the stud k^6 being mounted in a lever k^{10} , which is fulcrumed upon the upper end of the stud c^{12} . The oblique movement of the tool k as said tool is reciprocated back and forth by the bell-crank lever c^{15} is caused by a stud k^{11} , which is projected vertically from the inturned end of the arm or bracket k^7 , which stud k^{11} engages a slot k^{12} , formed in the shank k^2 of the stretching-tool k .

20 The above-described arrangement is such that the tool k will be moved up and down in unison with the movements of the tool F , and by means of the bell-crank lever c^{15} and the stud-and-slot connection described said tool k will be moved back and forth over the work 25 in an oblique direction, thus engaging the reinforcing material and exerting pressure thereon against the anvil or former E and taking up any slack or pucker which may be in the same.

30 The machine of the drawings comprises a trimming mechanism which acts upon the edge of the reinforcing material as the sole is fed along after the bead-forming tools have acted thereon and trims off the edge of said material to correspond to the edge of the insole. This trimming mechanism comprises a pair of disk-cutters m and m' , the cutter m being carried upon the forward end of a shaft m^2 and the cutter m' upon the forward end 40 of a shaft m^3 , the said shafts being mounted in suitable bearings in a carriage m^4 , which is arranged to have a movement toward and from the work-support C , for a purpose to be hereinafter described.

45 The shafts m^2 and m^3 are rotated simultaneously in opposite directions in the following manner: Shaft m^2 is extended beyond its bearings in the carriage m^4 , and upon the end thereof is a lug m^5 , which engages a slot m^6 in a drum m^7 , carried by a shaft m^8 , which is mounted to rotate in a bearing m^9 upon the upper end of a standard m^{10} , projecting upwardly from the base of the frame or head A' , and said shaft m^8 carries a belt-pulley m^{11} , which may be rotated by a belt from any suitable source of power to impart a rotary movement to the shaft m^8 and drum m^7 , and by means of the lug m^5 impart rotary movement to shaft m^2 , carrying the disk-cutter m . Upon shaft m^3 is a pinion m^{12} , which meshes with and drives a similar pinion m^{13} upon shaft m^3 , whereby a rotary movement will be imparted to the shaft m^3 by the shaft m^2 . Shaft m^2 is arranged to have a longitudinal sliding movement in its bearings in the carriage m^4 , and surrounding said shaft is a coiled spring m^{14} , which bears at one end

against the carriage m^4 and at its opposite end against a collar m^{15} , fixedly secured upon the shaft m^2 , whereby said spring will normally force the shaft m^2 backwardly in order to maintain the cutting edges of the cutters m and m' in close contact with each other to properly act upon and sever the projecting edge of the reinforcing material.

75 In order that the cutters m and m' may freely move toward and from the work-support C to accommodate themselves to the varying curve of the edge of the insole, the carriage m^4 is arranged to be freely movable back and forth from the work-support C .

80 In the machine of the drawings the carriage m^4 is connected by means of adjusting-screws m^{16} to a bar m^{17} , and said bar is pivotally connected at m^{18} to a pair of swinging levers m^{19} , which are fulcrumed at m^{20} to the fixed frame A' of the machine. One of the levers m^{19} has a projecting arm m^{21} , which is arranged to have a limited movement between adjusting screw-stops m^{22} , threaded in bearings in lugs m^{23} of the fixed frame A' , and said arm m^{21} is connected to one end of a spring m^{24} , the opposite end of which is fixedly secured to one of the lugs m^{23} .

85 The above-described arrangement is such that as the insole is fed along beneath the bead-forming tools the cutters m and m' are rapidly rotated by means of the pulley m^{11} to trim and cut off the surplus reinforcing material which projects beyond the edge of the insole, it being understood that the face of the lower cutter m' rests against the edge of the insole, which is superimposed upon the work-support C , and as the insole moves along the carriage m^4 , which is yieldingly pressed forward by the spring m^{24} , it will be permitted to move freely backward and forward toward the work-support C in order that the cutters m and m' will conform accurately to the contour of the edge of the insole and will 100 accurately trim and cut off the projecting edge of the reinforcing material along the line corresponding to the edge of the insole.

105 By means of the adjusting-screws m^{16} the bite or meeting edges of the cutters m and m' may be adjusted vertically to position said cutters relatively to the plane of the reinforcing material, and by means of the adjusting-screws m^{22} the horizontal movement of the carriage m^4 and the cutters may be 110 accurately adjusted. In the formation of a lipped insole the lip is oftentimes formed at varying distances from the edge of the insole, it being placed farther from the edge along the shank of the sole and nearer the edge 115 along the fore part, thus resulting in a variation in the width of the feather of the insole along the shank and fore part, and inasmuch as the carriage m^4 and the knives m and m' are freely movable toward and from the medial line of the sole it results that said knives 120 will automatically position themselves according to the variations in the width of the feather.

The operation of the machine of the drawings is as follows: The insole having been provided with a reinforcing-covering which has been temporarily cemented to the upper 5 face thereof along its medial line, leaving the edge of the reinforcing material loose and projecting over the edge of the lip and beyond the feather, is superimposed upon the work-support C. In placing the insole upon 10 the work-support C said work-support is depressed against the tension of its spring by a downward movement of the rod c', produced by means of the treadle, (not shown,) and the insole is placed in position with the lip 15 thereof against the bead-molding finger e² of the anvil or former E, and the projecting edge of the reinforcing material resting upon the upper surface of the anvil or former E and over the bead-molding finger e². The work- 20 support is then permitted to rise and the feather of the insole is clamped between the upper surface of the work-support and the lower surface of the fixed bead-forming tool G, said bead-forming tool G resting upon the 25 reinforcing material immediately over the feather of the insole. The rotation of the main shaft B now acts through the bell-crank lever d to force the presser-tool D against the reinforcing material upon the face of the in- 30 sole and presses said reinforcing material against the inner face of the lip, after which the bead-forming tool F is forced downwardly by the cam b⁶ and by means of the finger f' thereon presses the reinforcing material down 35 alongside of the outer side of the lip and against the feather, and the finger f⁸ will press the reinforcing material against the upper edge of the bead-molding finger e² of the anvil or former E. The presser-tool D is now raised, 40 releasing the insole, and the slide f¹⁰ moves toward the left in Fig. 3 by means of the lever f¹², thereby moving the bead-forming tool F to the left, and simultaneously with the movement of the bead-forming tool F to the left 45 the work-support C will be rotated one step, thus feeding the work toward the fixed tool G and the cutters m and m'. The tool G rests against the outer face of the lip and acts to press and smooth the reinforcing material 50 against the lip and upon the surface of the feather, and as the work continues to move toward the left the rotating cutters m and m' will sever the projecting edge of the reinforcing material and remove the same even with 55 the edge of the feather, as before described. After the bead-forming tool F has moved to the left to the limit of its stroke it is raised from the work and returned to the right in position to descend upon the reinforcing material at a 60 new point and mold the same, as before described. Prior to the action of the bead-forming tool F upon the reinforcing material the stretching-tool k has been raised by the arm k⁷ and moved forwardly by the bell-crank c¹⁵, 65 and as the tool F descends the spring k^{8*} de- presses the stretching-tool k and causes the same to engage the upper surface of the rein-

forcing material and press said reinforcing material against the anvil or former E, and upon a retraction of the stretching-tool k by 70 means of the bell-crank c¹⁵ said tool will drag over the reinforcing material and take up any slack or puckers which may have been therein, thus causing the reinforcing material to be evenly and accurately cemented to the in- 75 sole and lip without any objectionable puckering or wrinkling thereof.

Having thus described my invention and its mode of operation, I claim as new and desire to secure by Letters Patent of the United 80 States—

1. In a machine for reinforcing insoles, the combination with an anvil or former, of a plurality of bead-forming tools one of said tools being a fixed tool and another of said 85 tools being movable toward and from the fixed tool, substantially as described.

2. In a machine for reinforcing insoles, the combination with a presser-tool and an anvil or former, of a bead-forming tool, and means 90 to impart to said bead-forming tool a vertical reciprocating movement toward and from the anvil or former, and a laterally-reciprocating movement in the direction of the feed of the work, substantially as described. 95

3. In a machine for reinforcing insoles, the combination with a work-support and means to rotate the same step by step, of a bead-forming tool arranged to clamp the work against the work-support and means to move 100 said tool in the direction of rotation of the work-support while in engagement with the work, substantially as described.

4. In a machine for reinforcing insoles, the combination with an anvil or former, of a plurality of bead-forming tools arranged side by side and acting upon the work at different points, one of said tools arranged to turn down the reinforcing material over the lip and on the feather of the insole and the other 110 of said tools arranged to smooth and press the reinforcing material against the lip and feather and to guide the work, substantially as described.

5. In a machine for reinforcing insoles, the combination with a bead-forming tool, of a former or anvil and means to impart a vertical movement to the former or anvil toward and away from the working end of said tool, substantially as described. 115

6. In a machine for reinforcing insoles, the combination with a bead-forming tool, of a former or anvil and a pivoted support for said former or anvil arranged to permit a vertical movement thereof, substantially as de- 120 scribed. 125

7. In a machine for reinforcing insoles, the combination with a vertically-movable work-support and a vertically-movable anvil or former, of means to simultaneously move the 130 work-support and former or anvil, substantially as described.

8. In a machine for reinforcing insoles, the combination with a vertically-movable work-

support and a vertically-movable anvil or former, of means for causing a relative movement of the work-support and anvil or former toward and from each other and a simultaneous movement in the same direction, substantially as described.

9. In a machine for reinforcing insoles, the combination with a vertically-movable work-support and a vertically-movable anvil or former, of means actuated by the movements of the work-support acting to move the anvil or former, substantially as described.

10. In a machine for reinforcing insoles, the combination with a rotating work-support arranged to feed the work, of a stretching-tool arranged to have a movement toward and from the medial line of the insole, and connected mechanism for rotating the work-support and for actuating the stretching-tool, substantially as described.

11. In a machine for reinforcing insoles, the combination with the cutters and means to actuate them, of a carriage supporting said

cutters and a pair of pivoted levers supporting said carriage arranged to permit a free movement of the carriage and cutters toward and from the work, substantially as described.

12. In a machine for reinforcing insoles, the combination with an anvil or former, of a bead-forming tool movable vertically toward and from the anvil or former, a stretching-tool arranged to have a vertical movement toward and from the anvil or former and connections between the stretching-tool and the bead-forming tool whereby the movements of the stretching-tool are controlled by the movements of the bead-forming tool, substantially as described.

In testimony whereof I affix my signature in presence of two witnesses.

JOHN B. HADAWAY.
